WIREBOUND BOX OR CRATE

Walter F. Newhouse, Benton Harbor, Mich.

Application January 5, 1931. Serial No. 506,562

26 Claims. (Cl. 217—43)

This invention relates to wirebound boxes and crates of the kind in which cleats and sheet material are secured together by staples, to form the sides and ends or heads of the box or crate, and in which binding wires are arranged to encircle the box, each binding wire having its ends twisted together at one corner of the box, thereby to tension the wire tightly around the box.

Ordinarily, in boxes and crates of this kind, two of the binding wires extend along the sheet material over the cleats, and these binding wires are stapled and secured to the cleats, so that each wire extends across the gap or space between the adjacent ends of cleats. This construction, however, has been found to have some faults and disadvantages, because of the fact that the stapling of the wires to the cleats does not make the sheet material any the less liable to pull away from the cleats, by loosening the staples, and because the sheet material is free to bend or move outwardly and inwardly, causing the edge portion of the sheet material to fulcrum on the cleats, so to speak, and to thus gradually pry the staples loose, so that in tests and in actual practice these boxes have shown a tendency to weaken first along the joint between the sheet material and the cleats, and at the joints between the ends of the cleats. Moreover, with the binding wires stapled to the cleats, it has been common, both in tests and in actual practice, for these binding wires to slip off at the corners of the box, thus leaving the joint at any such corner of the box in a weakened condition.

Generally stated, therefore, the object of this invention is to provide a novel and improved construction and arrangement whereby no binding wires are stapled to the cleats, but instead wide staples, or any suitable staples, are inserted through the sheet material and into the cleats, in a manner to firmly attach the sheet material to the cleats, in combination with binding wires arranged to encircle the box at points immediately or suitably inside of the cleats, whereby the staples for securing these binding wires in place do not extend into the cleats, but simply extend through the sheet material at points a distance from the inner sides of the cleats, and are clinched on the inner surface of the sheet material, thereby lessening the tendency of the sheet material to pull away from the cleats, both in tests and in actual practice, and lessening the tendency of fracture at the points between the ends of the cleats, inasmuch as the said binding wires are back far enough from the heads or ends of the box to prevent these wires from slipping off over the corners of the box. More specifically considered, the invention contemplates the arrangement of the binding wires close enough to the cleats to prevent outward bulging of the side walls between the cleats and the wires, but far enough from said

cleats to prevent fulcruming of the sheet material on the cleats, by outward and inward bulging of the walls, thereby to reduce the loosening action and strain on the staples that secure the sheets to the cleats.

It is also an object to provide certain details and features of construction and combinations tending to increase the general efficiency and the desirability of a wirebound box or crate of this particular character.

To the foregoing and other useful ends, the invention consists in matters hereinafter set forth and claimed and shown in the accompanying drawings, in which—

Fig. 1 is a plan view of a wireless-cleat wirebound box blank embodying the principles of the invention.

Fig. 2 is a side edge view of said blank.

Fig. 3 is a plan view of a portion of said blank, illustrating the manner in which staples are applied to fasten the sheet material to the cleats.

Fig. 4 is a side edge view of the structure shown in Fig. 3 of the drawings.

Fig. 5 is a view similar to Fig. 4, showing another form of the invention.

Fig. 6 is a view similar to Fig. 3, showing another form of the invention.

Fig. 7 is a perspective of a wirebound box made from the blank shown in Fig. 1, showing the ends of the binding wires twisted together at one corner of the box.

Fig. 8 is a view similar to Fig. 3, showing a different form of the invention.

Fig. 9 is a detail sectional view of a portion of the box shown in Fig. 7, illustrating the resulting action of any tendency of the sheet material of the side walls to bulge outwardly between the binding wires.

Fig. 10 is a perspective of a wirebound box blank involving the principles of the invention, showing a different form of the invention.

Fig. 11 is a transverse section of the blank shown in Fig. 10, on a larger scale.

Fig. 12 is a fragmentary plan view of a portion of the blank shown in Fig. 10 of the drawings.

Referring to Figs. 1 to 4, inclusive, the invention comprises the sheets of veneer 1, 2, 3 and 4, or any other suitable sheet material, secured to the cleats 5, which latter may be of any suitable character, but which in the drawings are shown with tongue and groove joints or tenons between their ends, whereby the cleats interlock in the well known manner when the blank is folded into box form, as shown in Fig. 7 of the drawings. Wide staples 6 are employed for fastening the sheet material to the cleats, in the manner shown, it being understood that the grain of the wood, if the sheet material is veneer, extends at right angles to the length of the cleats, whereby the tops of the staples 6 extend crosswise of the

grain of the wood in the sheet material. In the cleats, the grain of the wood, if the cleats are made of wood, will extend lengthwise thereof. Binding wires 7, 7 and 8 are secured to the outer surface of the box blank by staples 9 in the manner shown, these staples being preferably skewed or turned at an oblique angle so that their heads will extend more or less crosswise of the grain of the wood in the sheet material.

When the preliminary blank, as shown, is converted into the ultimate box shown in Fig. 7 of the drawings, it will be seen that the ends of the binding wires are twisted together at 10 to cause the wires to tightly encircle the box. It will also be seen that the wires 7 are spaced a distance from the inner sides of the cleats, whereby the staples 9 do not enter or engage the cleats. With this arrangement, the wires 7 tend to counteract and prevent any tendency on the part of the sheet material to first bulge outwardly, under the pressure of the load, and to then spring back inwardly, which ordinarily results in a fulcruming of the sheet material on the cleats, with the edges of the sheet material and the outer edges of the cleats forming the fulcral points of this motion. The wires 7 prevent this fulcruming action, and consequently tend to prevent the loosening of the staples 6, and to prevent the sheet material from pulling away from the cleats, as would be liable to happen if the wires 7 were stapled to the cleats, in the ordinary manner, instead of being stapled merely to the sheet material at points spaced a distance from the inner sides of the cleats. In other words, with the construction shown and described, when the sheet material bulges outwardly, between the binding wires, under pressure of the load, or for any reason, the strain is not on the staples 6, but is on the binding wires 7, as well as on the binding wire 8, and hence the tendency of the staples 6 to become loosened is very greatly reduced.

In Fig. 5, the construction is similar to that previously described, but in this case the staples 6 are driven entirely through the cleats and have their ends clinched on the under side of the cleats.

In Fig. 6 of the drawings, the construction is similar to that previously described, but in this case the staples 6 are arranged obliquely and more or less crosswise of the longitudinal center of the cleats, in the manner shown, whereby there are not so many staple legs in line with each other as there are in Fig. 3 of the drawings.

In Fig. 8, the construction is similar to that previously described, but in this case the staples 6 are driven in two parallel rows, so to speak, with the members of one row in staggered relation to the members of the other row, whereby the staples overlap, so to speak, when viewed from above, and whereby there is no grain of the wood in the sheet material that is not straddled by some staple head.

From the foregoing, it will be seen that the invention contemplates a novel construction and arrangement of the parts of a wirebound box or crate, of such character that the bursting strain, or the outward pressure of the sheet material, is resisted at points spaced a distance from the inner sides of the cleats, thus reducing the strain on the staples that secure the sheet material to the cleats, and obviating the necessity of using binding wires over the cleats. This arrangement does not increase the number of binding wires that are necessary or desirable, and has the advantage that it brings the binding wires closer together,

reducing the capacity of the sheet material to bulge between them, without increasing the total number of the wires necessary for any given size of box. In addition, this arrangement permits the use of staples 6, or other suitable staples, in such a manner as to more advantageously and more effectively secure the sheet material to the cleats, inasmuch as these staples can have wider heads, which heads can extend at right angles, or much more at right angles, to the grain of the wood in the sheet material.

Furthermore, the staples 6 can be much wider than any staples 9 employed to secure the binding wires in place, thereby straddling more of the grain of the wood in the sheet material; and, in addition, the staples 6 can be arranged with their heads parallel with the inner and outer sides of the cleats, whereby each and every staple leg is as far as possible from either side of the cleats, but, if desired, the staples 6 can be arranged as shown in Fig. 6 of the drawings—for example, in larger or thicker or wider cleats, it being understood that the cleats can be of different lengths or thicknesses or widths, depending upon the size of box or crate to be made. And, furthermore, the binding wires 7 are desirably placed a distance from the inner sides of the cleats, as shown and described, sufficient to interrupt and prevent the outward bulging action of the side walls from reaching the staples 6, in the manner explained; but these wires 7 are nevertheless close enough to the cleats to practically prevent any outward bulging action of the side walls between these wires and cleats, there being only a relatively short space or distance between these wires and the staples 6, and with such arrangement it is not likely that the pressure of the load within could at any time cause an outward bulging action of the sheet material between the wires 7 and the staples 6, and any such tendency would be effectively resisted by the wires 7 to minimize the strain on said staples.

Any outward bulging action of the sheet material between the wires 7 and 8, using the wires 7 as a sort of fulcrum, as a matter of fact, tends to cause the sheet material to more tightly hug or bear upon the cleats, as illustrated in Fig. 9 of the drawings. In this view of the drawings, the dotted lines represent the outward bulge of the sheet material between the binding wires, so that the wire 7 in effect becomes a fulcrum, with the result that the outer edge portions of the sheet material are pressed more tightly against the cleats.

On the other hand, any outward pressure of the load at a point between the wire 7 and the cleat 5, very obviously, will be sustained pretty much entirely by the wire 7, as the commodities shipped in boxes or crates of this kind are ordinarily not of a character to concentrate the outward pressure at any one point of the inner surface of the sheet material, but is usually distributed thereover, and such commodities are usually of such character that the outward bulging pressure is pretty much entirely between the binding wires. Thus the wires 7, as explained, are close enough to the staples 6 to minimize the strain on these staples, but at the same time are far enough away to prevent the outward bulging of the side material between the wires from developing a fulcruming action of the sheet material on the cleats.

In Figs. 10, 11, and 12, the construction is similar to that shown in Fig. 1 of the drawings, but in this case the staples 11 for the three binding wires 7 and 8 are driven upwardly or outwardly

through the sheet material of the blank, whereby these staples have their points clinched on the outer surface of the blank, while the heads of these staples are flush with the inner surface of the blank. Preferably, as shown, the staples 11 are arranged with their heads extending obliquely, whereby the two legs or points of each staple are spaced apart on the wire 7, or on the wire 8, the clinched portions of the staple legs extending at right angles to the wire 7 or the wire 8, as shown more clearly in Fig. 12 of the drawings. These staple points are deflected in a way that bends them over the binding wires and downwardly against or even into the sheet material. In this way, the binding wires are sufficiently held in place, on the outer surface of the blank, while the inner ends of the staples, being formed by staple heads, are smooth and free from points or projections, and are thus not likely to scratch or injure the contents of the box or crate. As the heads or inner ends of the staples 11 are arranged obliquely, as shown, it follows that each staple straddles the grain of the wood of the sheet material, thus firmly anchoring each staple in the sheet material.

Thus it will be seen that in each form of the invention there are no binding wires extending across or over the gaps or joints between the ends of the cleats, and that the binding wires are so arranged that all outward bulging of the sheet material is first imposed as a strain on the binding wires, without imposing much if any disrupting or detaching strain on the fastening devices between the sheet material and the cleats. Preferably, for this purpose, as shown, and as illustrated in the drawings, as in Figs. 8 and 11, all of the binding wires are disposed between the two parallel planes of the inner sides of the cleats. The outer sides of the cleats are flush with the edges of the sheet material, and the inner sides of the cleats are in planes between the staples 6 and the binding wires 7 of the blank. But, in any event, there are wires close enough to the cleats (although not stapled thereto) to hold the cleat ends in engagement with each other, but without, or at least less, danger of any wires slipping off over the corners of the box.

Moreover, the staples 9 can be driven much closer to the meeting edges of the sheets, than if driven into the cleats, for staples could not be inserted in the tongue and grooves of the cleats.

It will also be seen that by locating the binding wires adjacent the cleats, inwardly a distance, so that they are not stapled to the cleats, these wires are not in danger of cutting into the tenons or joints between the ends of the cleats, in case of rough handling or rough usage. In other words, the wires cannot cut into the ends of the cleats and thereby contribute to the splitting or breaking of the cleats, as is common when the wires are fastened to and over the cleats.

Obviously, when no wires are stapled to the cleats, so that the staples which are driven into the cleats may extend exactly parallel with the sides of the cleats, it is possible to use narrow cleats and less wood.

It will be seen that the staples 6, in each form of the invention, are relatively wide, and have straight flat heads extending, in each form of the invention, more or less longitudinally of the cleats. In one case these staple heads are exactly parallel with the sides of the cleats, while in the other form of the invention these heads extend diagonally or obliquely of the cleats. But in each case these staples are sufficiently longi-

tudinal of the cleats to straddle a considerable amount of the grain of the wood of the sheet material, when wood veneer is used for this purpose, it being understood that the grain of the wood in the sheet material must extend transversely of the cleats and binding wires, in order to give the box the requisite strength.

What I claim as my invention is:

1. In a wirebound box or crate, the combination of solid one-piece cleats for the heads or ends of the box, said cleats being formed to engage each other at their ends, sheet material forming the side walls of the box, staples securing the sheet material to the cleats, driven with their heads tight against the sheet material, with the head of each staple extending more or less longitudinally of the cleats, binding wires encircling the box continuously between their ends, and staples securing said binding wires to the sheet material only, the ends of said wires being interconnected, whereby the wires tightly encircle the ultimate box, said binding wires being disposed a distance back from the heads or ends of the box, whereby the staples over said wires are spaced a distance from the inner sides of the cleats, and from said cleat staples, whereby all binding wires of the box or crates are disposed between the cleats at one end of the box and the cleats at the other end of the box or crate, but with a wire at each end of the box close enough to the cleat staples to practically prevent any bursting strain thereon and to maintain the engagement at the ends of the cleats with each other, thereby obviating the necessity of stapling any binding wires to said cleats.

2. A structure as specified in claim 1, the staples that secure only the sheet material to the cleats being wider than the staples that secure the wires to the sheet material, which latter staples are all clinched on the under or inner side of the sheet material, whereby the cleat staples are effectively arranged more or less crosswise of the grain of the wood of said sheet material when the latter is composed of wood veneer.

3. A structure as specified in claim 1, said cleat staples being inserted entirely through the cleats and having their ends or points clinched on the under side of each cleat.

4. A structure as specified in claim 1, said cleats having tongue and groove joints or tenons at their ends.

5. A structure as specified in claim 1, having at least one intermediate binding wire between said first mentioned binding wires, said wires cooperating to reduce or minimize the bursting strain of the side walls on the staples that secure only the sheet material to the cleats.

6. A structure as specified in claim 1, said wires being far enough from said cleats to prevent fulcruming of the sheet material on the cleats, when the side walls bulge outwardly between the wires, but near enough to said cleats to prevent outward bulging of the side walls between the wires and the cleats.

7. A structure as specified in claim 1, permitting insertion of some of said staples closer to the meeting edges of the sheets than would be possible if inserted in the cleats.

8. A structure as specified in claim 1, said cleat staples being inserted with their heads extending parallel with the sides of the cleats.

9. A structure as specified in claim 1, said cleat staples being inserted in rows, in staggered relation, with the staple heads in each row parallel with the sides of the cleats, and with the heads of

one row co-extensive with the spaces in the other row.

10. In a wirebound box or crate blank, the combination of sheet material forming side walls, solid one-piece cleats secured to the under side of said sheet material along the side edges of the blank, by staples that secure only the sheet material to the cleats, the head of each staple being straight and flat and extending more or less longitudinally of the cleats, and a plurality of parallel binding wires stapled to the upper or outer surface of the blank, provided with ends which can be interconnected on the ultimate box or crate, each and every binding wire of the blank being disposed at a point between the two parallel rows of cleats, with two of said binding wires spaced a distance from the cleats, but close enough to the cleats to obviate the necessity of stapling any binding wires over and to the cleats, whereby the blank has two lines of wireless cleat staples spaced a distance from two lines of binding wire staples, thereby to practically prevent any bursting strain on said cleat staples.

11. A structure as specified in claim 10, said binding wires adjacent the cleats being a distance back from the outer sides of the cleats sufficient to prevent the wires from slipping off the corners of the box or crate, when the same is subjected to rough treatment in use.

12. A structure as specified in claim 10, the staples which secure only the sheet material to the cleats having their heads arranged to extend parallel with the sides of the cleats.

13. A structure as specified in claim 10, said cleat staples being substantially wider than the staples that secure the wires in place.

14. In a wirebound box or crate blank, the combination of sheet material forming the sides or outer walls of the ultimate box or crate, when the blank is folded into box or crate form, one or more binding wires extending over the outer surface of the blank, adapted to externally circumscribe the ultimate box or crate, and staples inserted outwardly through said sheet material, from the inside of the box or crate, the staple heads being disposed on the inner surface of the sheet material, whereby the staple heads are inside the ultimate box or crate, and the staple legs or points being clinched over said wire or wires on the outer surface of the sheet material, on the outside of the box or crate.

15. A structure as specified in claim 14, said staples being inserted with their heads extending obliquely below the wires, and the staple points being curved over the wire or wires and downwardly at opposite sides thereof.

16. A structure as specified in claim 14, said staples being inserted with their heads extending obliquely below the wires, and the staple points being curved over the wire or wires and downwardly at opposite sides thereof, whereby the staple points are spaced apart on the binding wire.

17. A structure as specified in claim 14, the staple heads being substantially flush with the inner surface of the sheet material.

18. A structure as specified in claim 14, the staple heads being substantially flush with the inner surface of the sheet material, and the legs of each staple being disposed at opposite sides of the binding wire, and the staple points being bent over across the wire and downwardly into the sheet material.

19. A structure as specified in claim 14, the staple heads being substantially flush with the inner surface of the sheet material, and having the legs of each staple being disposed at opposite sides of the binding wire, and the staple points being bent over across the wire and downwardly into the sheet material, and the head of each staple being disposed obliquely below the binding wire, whereby the two staple points of each staple are spaced apart on the binding wire on the outer surface of the blank.

20. In a wirebound box or crate blank, the combination of sheet material forming the sides or outer walls of the ultimate box or crate, when the blank is folded, reinforcing means in the form of binding wire extending over the outer surface of the sheet material, forming external binding for the ultimate box or crate, and fasteners driven from the inside and outwardly through said material, from the inside of the box or crate, said fasteners having their heads disposed on the inner or under sides of the sheet material, and whereby the fastener heads are inside the ultimate box or crate, and having their outer ends clinched on the exterior of the box or crate on said binding wire.

21. A structure as specified in claim 20, said fastener heads being substantially flush with the inner surface of the sheet material.

22. A structure as specified in claim 20, said fasteners comprising staples.

23. In a wirebound box or crate blank, the combination of sheet material forming the sides or outer walls of the ultimate box or crate, when the blank is folded, binding wires extending over the outer surface of the sheet material, adapted to externally circumscribe the ultimate box or crate, solid one-piece cleats on the under side of the sheet material, flat headed staples inserted through the sheet material into the cleats, and means for securing said binding wires in place, said binding wires being spaced from the inner sides of said cleats and from said staples a distance close enough to prevent outward bulging of the sheet material between said staples and said wires, and to practically prevent any bursting strain on said staples, but far enough from the cleats to prevent fulcruming action of the sheet material on the cleats by outward bulging of the sheet material between said binding wires, whereby the box or crate has two lines of wireless cleat staples and two lines of binding wire staples spaced a co-operative distance therefrom.

24. In a box, side walls therefor of suitable sheet material, reinforcing means on the outer surfaces of the side walls, and staples inserted outwardly through the side walls and having their points clinched upon said reinforcing means, whereby the heads of the staples are inside the box.

25. A structure as specified in claim 24, said reinforcing means and side walls and staples being combined as stated to provide preformed side panels for the ultimate box.

26. A structure as specified in claim 24, said reinforcing means comprising encircling binding wires for the box, these wires extending under the clinched points of the staples, the heads of the staples extending diagonally, and the points of each staple extending substantially parallel and at right angles across the binding wire.

WALTER F. NEWHOUSE.
